CUSHION HEEL

Paul Maass, Hollis, N. Y.

Application May 8, 1948; Serial No. 25,909

3 Claims. (Cl. 36—36)

1

This invention is an improvement in cushion heels for shoes; and more particularly a rubber heel of such construction that the part thereof which usually becomes worn down with use can easily be replaced.

An object of the invention is to provide a rubber heel that is simple in design and that can be quickly and inexpensively produced; the heel being in two parts, one being fixed to the shoe and the other having the form of a section that can readily be attached and quickly removed when worn out to enable a new one to be substituted.

Another object is to provide a heel having a body or principal part with a replaceable section so fashioned that said section can be securely joined to the remainder of the heel in tight interfitting engagement; hence the stresses to which the heel is subjected in walking will have no effect to force the removable section out of proper position or distort the heel at any point.

The drawings illustrate preferred embodiments of my improvement; but I do not wish to be restricted to the precise articles which the drawings present. Changes in details may be made without departing from the general plan which characterizes my invention.

On the drawings:

Figure 1 is a bottom plan of the body of a rubber heel according to my invention, showing the removable section attached;

Figure 2 illustrates the body of the heel without the replaceable section;

Figure 3 is a vertical section on line 3—3 in Figure 1;

Figure 4 is a cross section on line 4—4 of Figure 1;

Figure 5 is a top plan of the removable section detached;

Figure 6 is a rear view of the heel without the replaceable part;

Figure 7 is a section of part of another form of heel according to my invention; the section lying in a plane running lengthwise of the shoe as in Figure 3; and

Figure 8 is a similar section showing a modified removable section.

On the drawings the rear portion of a shoe is indicated at 1. The shoe has a heel 2; and the rear of the body or main member of the heel has a cavity 3 extending forward and open at the bottom of the heel. The inner end or wall of this cavity presents a concave surface shown at 4 and the top or roof of this cavity has a low, flat protuberance 5. This protuberance is in the

2

middle of the cavity 3 and has transverse convex sides with rounded grooves 6, close to the roof of the cavity 3; and the sides of this protuberance joining the ends of the grooves are flat and straight as shown at 7. The height of the protuberance is less than half the height of the cavity 3.

The cavity is filled by a replaceable or member section 8, the sides of which are surfaces 10 which are convex, the curves intersecting at the ends. This gives the section the general configuration of a wide shuttle with pointed extremities. The section 8 and the recess 3 conform to each other in shape and the section is no thicker than the depth or height of the cavity, so that when the section is fitted into place, the heel presents the same surface formation as if it were all in one piece. The section 8 engages the projection 5 in tight interfitting engagement is held in proper position without adhesive or fastening means of any kind.

This result is assured by forming the section 8 with a depression 9 in the upper face of the section. The depression 9 is as deep as the height 25 of the protuberance 5, and of the same outline and extent. Crosswise of the heel, or in the direction of the greatest length of the section 8 the depression 9 has inward projecting rounded ribs 10 along its edges, and the sides 11 joining the ends of said ribs are flat and straight to match the sides 7 of the protuberance 5. When the section 8 is attached, the protuberance 5 is forced into the depression 9 and the ribs 10 enter the grooves 6 in the two transverse sides of the protuberance 5 and hold the section 8 and the body 1 of the heel together.

The protuberance 5 has small recesses 12, opening through the flat face or end of the projection 5 and being widened transversely as 40 shown in Figure 2. They taper somewhat, being widest at their outer open ends and narrowest at their closed inner ends. These recesses permit the protuberance to be squeezed together or contracted somewhat to facilitate attaching the section 8. In line with the apertures are tapering passages 13 that pass into the section 8 from the bottom. The inner ends 14 of these passages 13 pass into the section 8 from the bottom. The inner ends 14 of these passages or ducts are small, and they pass through the bottom of the depression 9, each being in line with one of the recesses 12. These ducts allow air to enter the recesses 12 while the section 3 is being put on, and the protuberance can then expand so as to prevent the section from getting loose and falling off.

Further the roof of the cavity 3 in the heel has transversely extending grooves 15 and the section 8 has curved ribs 16 running along the curved edges of the cavity 3 and section 8. The ribs taper to an edge on the top and the grooves have such form that the ribs fit snugly and fill them. This makes a further interlocking fit between the body of the heel and the section 8 to maintain the section in proper position and prevent distortion of the section 8. The ribs have inclined outer faces and steep inner sides or faces substantially perpendicular to the top of the section 8. The inclined faces of the ribs 16 are presented to the open rear of the cavity. Hence when the owner walks the steep faces or sides of the ribs 16 resist to advantage the force of the forward reaction thrust on the section 8, and assist the protuberance 5 in preventing displacement of the section 8.

In Figures 7 and 8 the protuberance 5' in the cavity 3 has angular grooves 6' in its transverse sides, and the depression 9' in the section 8 has ribs 10' that are angular in cross section; to enter the grooves 6'. Otherwise the cavity 3 and the section 8 are the same as above set forth.

In this embodiment the protuberance 5' may be concave on its face to engage the bottom of the depression 9' with a vacuum cup effect.

The recesses 12 taper only in the direction of the length of the shoe. See Figure 2. In a transverse place they do not taper, as indicated on Figure 4.

The section 8 is attached by bringing one end into position with one flat side 11 of the depression 9 adjacent one flat side 1 of the protuberance 5. This end is then pressed down and the adjacent end of the protuberance 5 is forced into the depression 9. This is accompanied by bending between the ends of the section, and the ducts 13 are thus widened slightly and opening, exhausting any air trapped in the recesses 12. As the section 8 is pressed further, the protuberance 5 enters the depression 9 fully; and the section 8 straightens to close the ducts 13. Any air still inside adds to the cushioning effect.

The curvature of the section 8 is the same on both sides. The section is therefore adapted to be attached to either shoe; and if after it has been worn for a time on one shoe it can be transferred to the other. It can also be reversed on either shoe, so as to change the forward inner edge to outer rear position. This presents a new wearing surface at the back of the heel and gives much longer wear to the heel.

Having described my invention, what I believe to be new is:

1. A heel for a shoe comprising a main member with a wide cavity extending into it from the rear and opening through the bottom of the heel, a removable member conforming in size and shape to the cavity, to fit the same snugly and

being flush with the outer surfaces of said heel, one of said members having a broad protuberance, and the other having a depression conforming in shape to the protuberance, said depression and said protuberance having interfitting means at the edges for joining the section to the heel, with said section and said protuberance in tight engagement within said cavity, the protuberance having recesses open through the outer face to enable it to be contracted for insertion into said depression, said heel having small ducts open to the air in position to communicate with said recesses.

2. A heel for a shoe comprising a body with a wide cavity extending into it from the rear and opening through the bottom of the heel, the roof of the cavity having a broad protuberance, a removable section conforming in size and shape to the cavity, to fit the same snugly and being flush with the outer surfaces of said heel, the section having a depression conforming in shape to the protuberance, said depression and said protuberance having interfitting means at the edges for joining the section to the heel, with said section and said protuberance in tight engagement, the protuberance having recesses open through the outer face to enable it to be contracted for insertion into said depression, said section having air ducts open at the bottom and in said depression, in position to communicate with said recesses.

3. A heel for a shoe comprising a body with a wide cavity extending into it from the rear and opening through the bottom of the heel, the roof of the cavity having a broad protuberance, a removable section conforming in size and shape to the cavity, to fit the same snugly and being flush with the outer surfaces of said heel, the section having a depression conforming in shape to the protuberance, said cavity having grooves adjacent said protuberance, and said section having ribs to fit into said grooves, some of said grooves being in the transverse sides of said protuberance, the remaining sides being flat, said protuberance having recesses open through its outer face and said section having ducts at the bottom of said depression connecting its outer face with said depression in line with said recesses.
